CLAIM

The ornamental design for a clamping support head as shown and described.

DESCRIPTION

FIG. 1 is a perspective view of a repair stand having a clamping support head according to our new design mounted thereto.

FIG. 2 is a top-rear perspective view of the clamping support head according to our new design.

FIG. 3 is a bottom-front perspective view thereof.

FIG. 4 is a top plan view thereof.

FIG. 5 is a bottom plan view thereof.

FIG. 6 is a left-side elevation view thereof.

FIG. 7 is a right-side elevation view thereof.

FIG. 8 is a front elevation view thereof; and,

FIG. 9 is a rear elevation view thereof.

Broken lines illustrate the repair stand, adjustment knobs, fasteners, fastener recesses, and interior features that form no part of the claimed design.

1 Claim, 9 Drawing Sheets
